UNITED STATES PATENT OFFICE

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

PRINTING-SLUG.

1,122,842.

Specification of Letters Patent.

Patented Dec. 29, 1914.

Original application filed June 18, 1914, Serial No. 845,753. Divided and this application filed November 2, 1914. Serial No. 869,750.

To all whom it may concern:

Be it known that I, WILLIAM R. ALLEN, a citizen of the United States, residing at Cleveland, in the county of Cuyahoga and State of Ohio, have invented a certain new and useful Improvement in Printing-Slugs, of which the following is a full, clear, and exact description, reference being had to the accompanying drawings.

10 This invention relates to printing slugs adapted to stand a short height-to-paper and of a form which may be readily mounted in grooved or slotted holders, as for example the Multigraph drum, slotted type plates, etc.

15 The objects of the invention are to provide such a slug in a form which may be very cheaply produced, will hold itself in place while in use, and will receive the printing pressure on an original cast surface, thus insuring accuracy of height.

20 This application is a division of my pending application No. 845,753, filed June 18, 1914, which relates to the process of making slugs.

25 The present invention comprises a slug having a T-head, a shank and a corrugated portion, pressed laterally from the shank some distance below the head and at the bottom of the slug. This corrugated portion, in conjunction with the overhanging head, provides in effect, grooves on the opposite sides of the slug, which hold it in place; at the same time, the construction admits of 30 the head, which carries the printing pressure, having its original cast form, thus insuring accurate height-to-paper. It is a characteristic of the corrugated or wavy ribs formed on the shank, that projections 35 on one side come opposite indentations on the other. It is possible therefore, not only to insert the slug lengthwise, like an ordinary grooved slug, but laterally, directly from the side of a member having a wavy slot, and hold the slug in place by shifting it slightly, lengthwise. The slug is illustrated in the drawings herein and is hereinafter 40 more fully described.

In the drawings Figure 1 is a perspective

view of my slug; Fig. 2 is a bottom view 50 thereof; Fig. 3 is a perspective view of the cast primary slug, from which the finished slug of Fig. 1 is produced; Fig. 4 is a cross section through suitable mechanism to act on opposite sides of the shank of the primary slug to corrugate it and shear off the lower portion; Fig. 5 is a plan of the corrugating blades of the apparatus shown in Fig. 4; Fig. 6 is a vertical section through an apparatus of the Mergenthaler type for 55 casting the slug shown in Fig. 3.

As shown in Figs. 1, 2 and 4, the slug of this invention has an overhanging head A carrying a line of characters B, and beneath this head and preferably located centrally 60 thereof, is a flat sided shank C. Adjacent to the lower edge of this shank on opposite sides thereof, are wavy ribs D and D'. These ribs come opposite each other and the projecting portions of one rib are opposite the 65 indentations of the other. Thus the ribs may be conveniently made by pressure against the opposite sides of a plane sided shank, by a pair of blades having complementary 70 sinuous edges. Such blades are shown in Fig. 75 5 and designated 10 and 11. The sinuous edges of these blades appear at 12 and 13 respectively, from which it will appear that the hump of one edge comes opposite the depression of the other. C in this figure, indicates the shank of the slug. It will be 75 seen that when such shank is pressed by the blades mentioned, the portions between the blades will be distorted in opposite directions, producing a scalloped or wavy rib on 80 85 each side of the shank.

Fig. 3 illustrates a primary slug adapted to be cast in a Mergenthaler or similar machine, and thereafter treated to make my finished slug. This primary slug has a head 90 A with the characters B, and has the shank C. The shank and head together, are preferably the standard height of line slugs, so that no change need be made in this regard, in the casting machine.

Fig. 6 illustrates a machine for casting 95 such a slug as shown in Fig. 3. 20 is the usual Mergenthaler mold wheel; 21 is a

solid mold having a narrow cavity 22 for the shank of the slug and a communicating larger cavity 23, for the head. 25 indicates a line of matrices adapted to stand against the mold; 26 is a melting pot on the opposite side of the mold, having a jet opening 27, communicating with the mold space 22. By such mechanism the slug shown in Fig. 3 may be easily cast with the regular Mergen-
10 thaler apparatus, equipped with a substituted mold. After casting, the slug is ejected and the sides of the head trimmed, and it is then ready for treatment to form wavy ribs and to shear off the shank below the
15 ribs. As the formation of the ribs by pressure from the body of the shank causes the ends of those ribs to project slightly beyond the original end of the shank, I taper such end of the shank inwardly adjacent to the
20 head, as shown at *c*, in Fig. 3. Accordingly, projections on the ribs beyond the edge of the shank, do no harm, as such extensions are still less than that of the cast head.

Fig. 4 illustrates a suitable apparatus for
25 corrugating and shearing the shank of the plug shown in Fig. 3. This apparatus consists briefly of a pair of corrugating blades 10 and 11, above referred to, a pair of knives 14 and 15, to which the blades are secured,
30 a pair of supporting plates 16 and 17 slidably mounted on the blades 10 and 11, and a pair of centering blocks 18 and 19, which may be rigidly secured to the knives and the blades 10 and 11, and movably carry the
35 supporting plates 16 and 17. These plates are normally pressed a limited distance toward each other by springs 30. The parts mentioned may be mounted in two holders 31 and 32, which are adapted to be caused to
40 approach or recede from each other.

With such an apparatus as described, the holders being a suitable distance apart, such a slug as shown in Fig. 3 is dropped into place between the separated parts, the head
45 resting on and being supported by the plates 16 and 17; then the holders 31 and 32 are caused to approach each other (the supporting plates moving relatively backward) and the blades 10 and 11 corrugate the
50 shank to produce the wavy ribs on opposite sides, and the knives 14 and 15 shear off the shank immediately below the ribs. During this operation, it is preferable to hold the slug firmly seated on the plates 16 and 17,
55 by pressure against its face,—for example by a roller (indicated by the broken line 35) which may be moved out of the way to allow the slug to be placed, but in operation is suitably pressed downward. Fig. 4
60 shows the final position of the parts,—the knife edges meeting, the blades having moved past the respective faces of the shank, the plates having relatively receded until their outer ends abut fixed stops, and the

edges of the blocks abutting the sides of the 65 head.

Such an apparatus as last described is shown more fully in my parent application No. 845,753. Essential features thereof are also shown and claimed in a prior application of Harry C. Gammeter, No. 835,478, filed April 30th, 1914.

Having thus described my invention, what I claim is:

1. A line slug adapted to stand a short 75 height-to-paper and comprising a head and a shank, the shank having a corrugated portion some distance below the head.

2. A printing slug comprising a shank, a head projecting in opposite directions from 80 the shank, and corrugations formed from the body of the shank and projecting in opposite directions and spaced below the head.

3. A printing slug consisting of a T-head, a shank, and corrugations adjacent to the 85 lower edge of the shank and formed on opposite sides of the shank and spaced below the T-head.

4. A printing slug comprising a T-head and a shank, the material of the shank adjacent to its lower edge and some distance 90 below the T-head being pressed in opposite directions to make lateral projections on each side, giving the effect of a grooved slug.

5. A line slug having a longitudinal shank, a longitudinal T-head thereon, characters on the T-head, the shank at its lower end and for some distance above that end being made wavy to produce projections on 100 opposite sides of the shank, said projections being spaced a material distance below the under face of the T-head.

6. A line slug having a T-head, a shank and wavy ribs on opposite sides of the shank 105 spaced from the head, projections on the rib at one side coming opposite indentations of the rib on the other side.

7. A line slug comprising an overhanging head, a shank, and ribs at the bottom 110 of the slug on opposite sides of the shank, said ribs being opposite each other and each rib having projections extending beyond the sides of the rib and indentations extending beneath the shank, the projections of one 115 rib coming opposite the indentations of the opposite rib.

8. As a new article of manufacture, a line slug having a head with an original cast under surface, a shank depending from 120 the head, and wavy ribs on opposite sides of the shank some distance below the head, the projections of the ribs of one side being opposite the indentations of the rib on the other side.

9. A line slug comprising an overhanging head, a shank, interrupted ribs on the opposite sides of the shank, each rib consist-

ing of projections and indentations, the projections on one side being opposite the indentations on the other.

10. A line slug comprising an overhanging head, a shank, and outwardly pressed projections on each side of the shank opposite indentations into the shank.

In testimony whereof, I hereunto affix my signature in the presence of two witnesses.

WILLIAM R. ALLEN.
